(57) **CLAIM**

The ornamental design for a separator, as shown and described.

DESCRIPTION

FIG. 1 is a top isometric view of a first embodiment of my new design for a separator;

FIG. 2 is a bottom isometric view thereof;

FIG. 3 is a top view thereof;

FIG. 4 is a bottom view thereof;

FIG. 5 is a bottom end view of FIG. 3;

FIG. 6 is a top end view of FIG. 3;

FIG. 7 is a left side view of FIG. 3;

FIG. 8 is a right side view of FIG. 3;

FIG. 9 is a top isometric view of a first variation of the first embodiment of my new design for a separator;

FIG. 10 is a bottom isometric view thereof;

FIG. 11 is a top view thereof;

FIG. 12 is a bottom view thereof;

FIG. 13 is a bottom end view of FIG. 11;

FIG. 14 is a top end view of FIG. 11;

FIG. 15 is a left side view of FIG. 11;

FIG. 16 is a right side view of FIG. 11;

FIG. 17 is a top isometric view of a second variation of the first embodiment of my new design for a separator;

FIG. 18 is a bottom isometric view thereof;

FIG. 19 is a top view thereof;

FIG. 20 is a bottom view thereof;

FIG. 21 is a bottom end view of FIG. 19;

FIG. 22 is a top end view of FIG. 19;

FIG. 23 is a left side view of FIG. 19;

FIG. 24 is a right side view of FIG. 19;

FIG. 25 is a top isometric view of a third variation of the first embodiment of my new design for a separator;

FIG. 26 is a bottom isometric view thereof;

FIG. 27 is a top view thereof;

FIG. 28 is a bottom view thereof;

FIG. 29 is a bottom end view of FIG. 27;

FIG. 30 is a top end view of FIG. 27;

FIG. 31 is a left side view of FIG. 27;

FIG. 32 is a right side view of FIG. 27;

FIG. 33 is a top isometric view of a second embodiment of my new design for a separator;

FIG. 34 is a bottom isometric view thereof;

FIG. 35 is a top view thereof;

FIG. 36 is a bottom view thereof;

FIG. 37 is a bottom end view of FIG. 35;

FIG. 38 is a top end view of FIG. 35;

FIG. 39 is a left side view of FIG. 35;

FIG. 40 is a right side view of FIG. 35;

FIG. 41 is a top isometric view of a first variation of the second embodiment of my new design for a separator;

(Continued)

FIG. 42 is a bottom isometric view thereof;
 FIG. 43 is a top view thereof;
 FIG. 44 is a bottom view thereof;
 FIG. 45 is a bottom end view of FIG. 43;
 FIG. 46 is a top end view of FIG. 43;
 FIG. 47 is a left side view of FIG. 43;
 FIG. 48 is a right side view of FIG. 43;
 FIG. 49 is a top isometric view of a second variation of the second embodiment of my new design for a separator;
 FIG. 50 is a bottom isometric view thereof;
 FIG. 51 is a top view thereof;
 FIG. 52 is a bottom view thereof;
 FIG. 53 is a bottom end view of FIG. 51;
 FIG. 54 is a top end view of FIG. 51;
 FIG. 55 is a left side view of FIG. 51;
 FIG. 56 is a right side view of FIG. 51;
 FIG. 57 is a top isometric view of a third variation of the second embodiment of my new design for a separator;
 FIG. 58 is a bottom isometric view thereof;
 FIG. 59 is a top view thereof;
 FIG. 60 is a bottom view thereof;
 FIG. 61 is a bottom end view of FIG. 59;
 FIG. 62 is a top end view of FIG. 59;
 FIG. 63 is a left side view of FIG. 59; and,
 FIG. 64 is a right side view of FIG. 59.
